PISTON CLEANING MACHINE

William A. Coninx, St. Paul, Minn.

Application November 24, 1948, Serial No. 61,847

5 Claims. (Cl. 15—21)

1

My invention relates to an improvement in piston cleaning machines wherein it is desired to provide a simple and effective means of cleaning the outer surface of a piston or similar article.

In the repairing and rebuilding of internal combustion engines such as automobile engines and the like, it is usual practice to remove the pistons from the motor and to clean the coating of carbon from the surface thereof. This is usually done on a wire buffing wheel or similar device. The piston must be held against the buffing wheel and rotated so that the entire surface of the piston is subjected to the buffing action. The top end of the piston is also buffed to remove the deposit therefrom. Several minutes' time is usually required to clean each piston.

It is the object of the present invention to provide a simple and effective device for cleaning the outer surfaces of pistons. The pistons are merely placed in my device and are automatically subjected to a buffing action, both on the head end and about the skirt or piston wall. Thus while the operator is removing the piston rings, replacing piston rings, or doing some other task, the piston may be automatically cleaned.

A feature of the present invention lies in the provision of a piston cleaning means which is variable to accommodate pistons of numerous sizes. As a result the piston may be quickly mounted in place for cleaning or quickly removed from cleaning position.

A feature of the present invention lies in the provision of a piston cleaning device employing liquid for assistance in dissolving the deposit on the piston surfaces. It is usually necessary to buff the pistons in a relatively dry state to prevent excessive spattering of the cleaning liquid from the buffing wheel. My piston cleaning device is mounted within a closed cabinet so that liquid can be used in the cleaning operation without spraying the operator with the cleaning solution.

A feature of the present invention lies in the provision of a piston cleaning device including a cabinet having a closure therefor and in mounting the piston buffing wheel for pivotal movement with the closure. As a result the buffing wheel is automatically disengaged from the surface of the piston at the same time the cover of the cabinet or housing is open.

These and other objects and novel features of my invention will be more clearly and fully set forth in the following specification and claims.

2

In the drawings forming a part of my specification:

Figure 1 is a side elevational view of my device in closed position.

5 Figure 2 is an elevation view of the opposite side of the device from that illustrated in Figure 1.

Figure 3 is a sectional view through the casting on the line 3—3 of Figure 4 showing the relationship of the various parts therein.

10 Figure 4 is a transverse section view through the cabinet, the position of the section being indicated by the line 4—4 of Figure 2.

Figure 4 is a transverse section view through the cabinet, the position of the section being indicated by the line 4—4 of Figure 2.

The piston cleaning apparatus A includes a 15 housing or cabinet indicated in general by the numeral 10. The cabinet 10 includes a rear wall 11, a front wall 12, and opposed end walls 13 and 14. A hopper shaped bottom 15 may, if desired, be supported between the end walls 13 and 14 and a drain 16 may be provided at the lowest point of the bottom. A screen 17 may be positioned above the bottom 15 so as to prevent large particles of material from entering the drain. If desired the bottom 15 may be removable for cleaning and the like.

20 The casing closure includes a curved top panel 19 having integral end panel portions 20 and 21 connected to opposite ends thereof. The end panel 21 lies in overlapped relation with the upper edge 22 of the end wall 14 and preferably lies inwardly thereof so that cleaning fluid draining down the walls of the end panel 21 will drop within the end wall 14. The end panel 20 at the opposite end of the curved top panel 19 overlaps 25 with a second panel 23. The second panel 23 in turn overlaps an upwardly extending edge 24 forming a part of the end wall 13.

25 A bracket or standard 25 is provided rearwardly of the casing and supports a suitable transversely extending shaft 26. A top supporting bracket 27 is bolted or otherwise secured to the shaft 26. The bracket 27 includes a downwardly extending flange 29 which is pivotal with respect to the shaft 26 into position directly above the rear wall 11. A back panel 30 is mounted on the bracket flange 29 to pivot therewith. The end wall panel 23 is secured to the rear panel 30 and pivots therewith. A hinge 31 is provided between the rear wall panel 30 and the curved top panel 19.

30 A front closure panel 32 is hingedly connected at 33 to the forward edge of the curved top panel 19. This front closure panel 32 is so designed as to be guided into overlapping relation 35 with the upper end 34 of the front cabinet wall

12. Thus when the closure is in the position illustrated in the drawings the operating mechanism is entirely enclosed.

The entire closure may if desired comprise a series of walls rigidly connected together. In other words, the hinges 31 and 33 may be eliminated and the rear wall 30 and front closure panel 32 may form a part of the top wall 19. However, with the particular structure illustrated the top portion of the closure may be hinged to permit ready access to the upper buffing wheel which will be later described.

A bearing 35 may be mounted upon the end wall panel 23 or otherwise supported in fixed relation to the shaft 26. The bearing 35 is designed to support a rotatable shaft 36. One end of the shaft projects into the cabinet 10 and supports an elongated buffing wheel 37. The buffing wheel is held in place by any suitable means against a collar 39 on the shaft 36 by a nut 40 or other suitable means. The portion of the shaft 36 outwardly of the cabinet 10 supports a pulley 41.

A double pulley 42 is rotatably supported upon the shaft 26. One portion of the pulley 42 is connected to the pulley 41 by means of a driving belt 43. The other portion of the double pulley 42 is connected by a second belt 44 to a pulley 45 mounted upon the drive shaft 46. The drive shaft 46 is connected to any suitable source of supply of power such as an electric motor, not illustrated in the drawings. The shaft 46 may be supported by suitable bearings such as 47 on the standard 25.

It will be noted that the shaft 36 is supported by the end wall panel 23 which is hingedly connected to the bracket 27 which rotates about the axis of the shaft 26. Thus the distance between the shafts 26 and 36 remains constant allowing the closure to hinge about the shaft 26 without difficulty. A resilient roller 49 is mounted upon a transverse shaft 50 supported by the casing end walls 13 and 14. The shaft 50 extends through the end wall 14 and is provided with a pulley 51 on its extremity. The pulley 51 is connected by a belt 52 to a cooperable pulley 53 on the drive shaft 46. Thus rotation of the drive shaft acts to rotate the resilient roller 49.

A pivot shaft 54 is supported between the end walls 13 and 14. A pair of spaced arms 55 are pivotally supported on the shaft 54 and are connected by a connecting plate 56 to insure pivotal movement of the arms in unison. A shaft 57 is supported by the free ends of the arms 55 and a resilient roller 59 is rotatably supported upon the shaft 57. The shaft 57 extends through an arcuate slot 60 in the casing wall 14. A pulley 61 is provided on the shaft 57 externally of the cabinet. A resilient belt 62 connects the pulley 61 with a cooperable pulley 58 on the shaft 50. The resilient belt 62 is capable of stretching or contracting to allow for variations in the distance between the shafts 50 and 57.

A threaded operating rod 63 extends through a slot in the plate 56 and into a threaded boss 64 held from axial movement on a threaded shaft 79. The spring 66 is interposed between the adjusting nut 65 on the rod 63, and the pivotal plate 56. By rotating the handle end 67 of the operating rod 63, the pivotal adjustment of the plate 56 and the arms 55 connected thereby may be varied. In other words, by rotation of the adjusting rod 63 the arms 55 may be pivoted in a counter-clockwise or a clockwise direction to change the position of the roller 59.

A third resilient roller 69 is supported upon a transverse shaft 70 between a pair of arms 71 rotatably supported upon a fixed transverse shaft 72. A plate 73 connects the arms 71 to insure rotation of both arms in unison about the shaft 72. Links 74 are pivotally connected at 75 to the plate 73 and are pivotally connected at 76 to a cross head 77 on a threaded shaft 79. The threaded shaft 79 extends through the front wall 12 of the cabinet and is equipped with a hand wheel 80 by means of which the shaft may be rotated. By rotating the shaft 79 the cross head 77 may be moved longitudinally along the axis of the shaft, thus pivoting the arms 71 in a clockwise or counterclockwise direction about the fixed pivot shaft 72. This swings the rubber roller 69 toward or away from the roller 49. The shaft 70 extends through the end wall 14 of the cabinet, extending through a curved slot 81 therein. A pulley 82 is mounted upon the shaft 70 externally of the cabinet 10. A resilient belt 83 connects the pulley 82 to a cooperable pulley 84 on the shaft 50 and is driven thereby. Variations in the distance between the shafts 50 and 70 merely stretches or contracts the resilient belt 83.

A shaft 85 is supported by a suitable bearing on the cabinet end wall 13 and extends through the end wall. On the end of the shaft within the cabinet 10 I provide a buffing wheel 86 which is arranged with its wires generally parallel to the axis of the shaft 85. The buffing wheel 86 is held in place by a suitable clamping nut 87 recessed into the buffing wheel. The end of the shaft 85 externally of the cabinet 10 is equipped with a pulley 89 which is connected by a belt 90 to a cooperable pulley 91 on the drive shaft 46. A plunger shaft 92 is supported by the cabinet wall 14 to slide transversely in parallel relation to the rollers 49, 59, and 69. The shaft 92 is splined to its support so as to be held from rotation, or, if desired, the plunger shaft 92 may be held from rotation by means of an integral arm 93 which extends about the parallel shaft 54. An arm 93 is connected to the shaft 92 to extend radially with respect thereto. The arm 93 supports one or a series of rollers 94 which are rotatable about the rod 93. A spring 95 is interposed between the casing walls 14 and the arm 93 to urge the arm toward the buffing wheel 86. This arm 93 is designed to urge the pistons being cleaned against the buffing wheel 86 so that the end of the piston may be cleaned.

The shaft 92 is provided with a pivotally attached handle 96 thereupon by means of which the shaft may be pulley outwardly, compressing the spring 95. A notch 97 is provided in a bracket 99 supported on the housing wall 14 adjacent the shaft 92. A pin 100 on the handle 96 is engageable with the notch 97. When the shaft 92 is pulley out a sufficient distance the pin 100 on the handle end 96 may ride over the bracket 99 and engage in the notch 97 to hold the shaft 92 in outward position.

A pipe 102 is supported adjacent the roller 59 and is connected by a conduit 103 to a suitable supply of cleaning liquid. The tube 102 is provided with a series of spaced apertures therethrough through which the cleaning fluid may flow. When the device is in operation fluid is forced through the tube 102 and is sprayed over the top of the roller 59 and against the surface of the piston 104 supported between the rollers 49, 59, and 69. The liquid is preferably sprayed by a suitable pump, not illustrated in the drawings, which receives the liquid from the drain 16

and forces it under pressure against the piston. The pump usually is connected to the drive shaft 46 for operation in unison with the remainder of the apparatus.

In operation a piston 104 is placed between the rollers 59 and 69 to rest upon the roller 49. The hand wheel 80 is usually rotated in one direction to pivot the roller 69 away from the roller 49 a distance sufficient to allow the piston to enter between the rollers 59 and 69. The hand wheel 80 is then rotated in a reverse direction until the roller 69 is drawn against the surface of the piston 104.

The casing closure is then swung in a counter-clockwise direction as viewed in Figure 3 of the drawings until the buffering wheel 37 engages the surface of the piston. As the closure is pivoted into closed position a switch is preferably actuated to start the source of power supply which rotates the shaft 46.

Rotation of the shaft 46 acts through the belts 44 and 43 to drive the buffering wheel 37. Simultaneously the drive shaft 46 starts the buffering wheel 86 into operation through the belt 90. At the same time the shaft 50 is rotated, driving the shafts 57 and 70 in unison therewith.

Operation of the shafts 50, 57 and 70 causes rotation of the rollers 49, 59 and 69 in unison. These rollers contact the outer surface of the piston 104 and slowly rotate the piston. As the piston rotates about its axis the exterior surface of the cylindrical piston wall or skirt contacts the buffering wheel 37 and is cleaned thereby.

Before starting the drive shaft in operation the end 99 of the lever 100 is disengaged from the notch 97, allowing the arm 98 and its rollers 94 to engage against the open end of the piston. The spring 95 urges the piston against the buffering wheel 86, thereby cleaning the closed or head end of the piston as the same rotates.

In accordance with the patent statutes, I have described the principles of construction and operation of my piston cleaning apparatus, and while I have endeavored to set forth the best embodiment thereof, I desire to have it understood that obvious changes may be made within the scope of the following claims without departing from the spirit of my invention.

I claim:

1. A piston cleaning apparatus for cleaning pistons having a generally cylindrical side wall and a closed head end, the apparatus comprising an open top casing, a pivotal cover for closing said casing, means for rotatably supporting a piston on a substantially horizontal axis within said casing, and a buffering wheel rotatably carried by said cover on a substantially horizontal axis and engageable with said piston side wall when said cover is pivoted into closed position.

2. A piston cleaning apparatus for cleaning pistons having a generally cylindrical side wall and a closed head end, the apparatus comprising an open top casing, means for rotatably supporting a piston within said casing, a cover for closing said open top of said casing, a shaft journalled in one end of said cover and extending into said cover, a buffering wheel carried by the shaft portion extending into said cover, a pulley carried by said shaft external of said cover, a second shaft in parallel spaced relation with said first shaft, a pulley on said second shaft, bracket

means connected with said cover and pivotally supported on said second shaft, and belt means trained over said pulleys, whereby the cover may be opened and closed by pivoting said bracket 5 means about said second shaft, said buffering wheel engaging said piston in closed position of said cover.

3. A piston cleaning apparatus for cleaning pistons having a generally cylindrical side wall and a closed head end, the apparatus comprising 10 roller means on which the piston may be supported, said roller means and the supported piston being arranged on parallel axes, a buffering wheel engageable with the head end of the piston, 15 roller means engageable with the other end of the piston, a plunger supporting said roller means substantially radial to the axis of the supported piston, means including a spring biasing said plunger toward the supported piston, said spring 20 thereby urging said piston against said buffering wheel, and latch means for holding said plunger in a retracted position.

4. A piston cleaning apparatus for cleaning pistons having a generally cylindrical side wall and a closed head end, the apparatus comprising 25 a roller on which the piston may be supported in axial parallel relation, a pair of rollers engageable with the side wall of the piston in angularly spaced relation to the first roller, respective 30 pivotally mounted arm means for rotatably supporting each of said pair of rollers, transverse shaft means on a plane substantially normal to the roller axes, a pair of elements on said shaft means, a threaded connection between said shaft 35 means and one of said elements, rotation of said shaft moving said one element longitudinally, and respective link means connecting between said elements and said arm means, the other of said elements being held from movement with respect 40 to said shaft means.

5. The structure described in claim 4 in which the link means connecting said other of said elements and its arm means constitutes a rod having a threaded end threadedly received in said 45 one of said elements, whereby the effective length of said last referred to link means may be adjusted to thereby move one roller of said pair of rollers relative to the other.
